Henry Hebbard, of New York, N. Y.
Letters Patent No 1114 - Dated July 5-1859.

The schedule referred to in these Letters Patent, and making part of the same,

To all whom it may concern:

Be it known that I, Henry Hebbard, of the City, County

Dec. 11/14

and State of New York, have invented or produced a new ornamental design for ornamenting the handles of Spoons, Forks, or other articles of table cutlery, whether made of silver, or other metal, and I do hereby declare the following to be a full description of the same, reference being had to the accompanying drawings forming a part of this specification the same letters of reference wherever they occur referring to like parts.

Figure 1. is the obverse side of a Spoon.

2. is the reverse side of the same.

Letter a. represents the bowl of the Spoon, b, the stem of the handle, and c, the shield. Around the edge of the stem and shield, is a raised thread d, which forms a margin to the handle of the Spoon, and terminates at its junction with the bowl of the Spoon in a double thread f, and having their ends united and bent upwards, so as to approach each other in the middle of the handle.

Between the ends of the united and converging threads f, is a raised drop g, upon which, is supported a tulip shaped device h, having a drop i, in the head of it.

Down the handle of the Spoon is a raised stem j, having on the head of it a ball k, upon which is supported a five pointed tulip shaped device l, as a Capital to the raised Columnar stem j, so as to give a Sceptre like appearance to the stem of the Spoon, at each side of the head of the stem are three pointed leaves m, which vanish at their lower edges in the sides of the stem.

On the margins of the shield are two raised threads n, which terminate in scroll points at the upper and lower ends of the shield, and on opposite sides of the device l, and a pendent three pointed leaf p, or fleur de lis, supported upon a scroll q, intervening between the ends of the outer marginal raised threads n, as forming the borders of the shield, to complete the ornamental device for the obverse side of the spoon.

On the reverse side of the spoon the same figures and ornamental devices are used, except, that the stem j² is concave, instead of convex as on the obverse side of the spoon, and that it terminates at the heel of the spoon in a broad triangular shaped seven lobed leaf r, each lobe being three pointed and thus covering the heel of the spoon to complete the ornamental device for the reverse side of the spoon.

Having now described my invention, I will proceed to set forth

3

Dec. 1114

what I claim and desire to secure by letters patent of the United States.

What I claim is the combination and arrangement of the several devices hereinbefore described; with the handle of a Spoon, fork, or other article of table cutlery, whether made of Silver or other metal, for the purpose of ornamenting the handles thereof.
